UNITED STATES PATENT OFFICE.

GUSTAVE REHMANN, OF NEWARK, NEW JERSEY.

DESIGN FOR A POCKET-CASE.

SPECIFICATION forming part of Design No. 35,022, dated September 3, 1901.

Application filed April 17, 1901. Serial No. 56,824. Term of patent 14 years.

To all whom it may concern:

Be it known that I, GUSTAVE REHMANN, a citizen of the United States, residing at Newark, in the county of Essex and State of New Jersey, have invented and produced a new and original Design for Pocket-Cases, of which the following is a specification, reference being had to the accompanying drawings, forming a part thereof.

10 This invention relates to a novel design for a pocket-case, the following description being given for the purposes of this specification and the drawings being mainly relied upon to elucidate the general features and to 15 illustrate the new esthetical effect produced.

The design consists, essentially, in the general appearance and beauty of the pocket-case herein described, having a body and a cover of an oblong appearance, the narrow 20 sides being convex and the two faces of the case being formed with longitudinal convolutions of varying widths, as shown, the respective ends of the said body and cover being made convex and having scallop-shaped 25 marginal edges.

The said pocket-case is illustrated in the accompanying drawings, which form a part of this specification, and in which similar letters of reference are employed to indicate cor-

30 responding parts.

Figure 1 is a face view of the pocket-case embodying the features of my novel design. Fig. 2 is a view of one of its narrow sides, and Fig. 3 is an end view of the case.

35 In the said drawings, A indicates the pocket-case embodying the features of my novel design, the same consisting, essentially, of a

body portion a and a cover a' , one fitting upon the other, and when viewed from the front or back being of a rectangular configuration 40 in its general appearance and having the two convex sides a^2 . The front and back faces of the pocket-case A are formed with the longitudinal convolutions a^3 , of varying widths, having an arrangement of alternately - disposed wide and narrow convolutions and the convolutions of the cover forming a continuation of the convolutions of the body portion of the case A when the cover is closed, as clearly represented in Fig. 1 of the drawings, 45 but otherwise having the general appearance illustrated in Fig. 2 when the case is viewed from the edge. The respective ends a^4 and a^5 of the body portion a and the cover a' are made convex, as indicated by the curved lines 50 a^6 , the said convex ends being bounded by the scallop-shaped marginal edges a^7 , formed by the junction of the longitudinal convolutions a^3 and the curved or convex surfaces of said ends a^4 and a^5 , as clearly illustrated in 55 the several figures of the drawings.

Having thus described my design, what I claim as new, and desire to secure by Letters Patent, is—

The design for a pocket-case substantially 65 as herein shown and described.

In testimony that I claim the invention set forth above I have hereunto set my hand this 16th day of April, 1901.

GUSTAVE REHMANN.
